SPECIFICATION forming part of Design No. 26,721, dated March 2, 1897.

Application filed January 22, 1897. Serial No. 620,272. Term of patent 3½ years.

To all whom it may concern:

Be it known that I, WINTHROP L. JACOBS, citizen of the United States, residing at East Orange, county of Essex, and State of New Jersey, have invented a new Design for Carpet and Border, of which the following is a specification.

This invention comprises two parts—namely, the design A for a carpet and the design B for a border; and I do hereby declare that the drawing accompanying this specification conveys to any one a clear understanding of the same and is sufficient to enable such person to use my invention.

The design A is characterized by a nondescript pattern spreading over its face and made up of curving stembork and flower-forms, the same constituting its leading feature.

The design B is characterized by an inner or-

namental band of stembork and flower-forms and an outer band made up of connected parallel figures, the same constituting its leading feature.

What I claim as new, and desire to secure 25 by Design Letters Patent, is—

1. In the design for a carpet, the body A, substantially as shown.

2. In the design for a carpet, the border B, substantially as shown. 30

3. The design for a carpet consisting of the body A, and the border B, substantially as shown.

In testimony whereof I have signed my name to this specification in the presence of 35 two subscribing witnesses.
